UNITED STATES PATENT OFFICE.

ETHAN I. DODDS, OF ZELIENOPLE, PENNSYLVANIA, ASSIGNOR TO KERNER MANUFACTURING COMPANY, OF PITTSBURGH, PENNSYLVANIA, A CORPORATION OF PENNSYLVANIA.

METHOD OF MAKING STAY-BOLTS.

1,226,480.

Specification of Letters Patent. Patented May 15, 1917.

Application filed July 6, 1914. Serial No. 849,036.

To all whom it may concern:

Be it known that I, ETHAN I. DODDS, a citizen of the United States, residing at Zelienople, in the county of Butler and State 5 of Pennsylvania, have invented a new and useful Method of Making Stay-Bolts, of which the following is a full, clear, and exact description, reference being had to the accompanying drawings, forming part of 10 this specification, in which—

Figure 1 is an end view of a blank from which I make bolts by my improved method.

Fig. 2 is a similar view of another form of blank.

15 Fig. 3 is a similar view of still another form of blank.

Figs. 4, 5 and 6 are similar views of other forms of blanks.

Fig. 7 is a transverse sectional view 20 through a die showing the blank after a portion has been punched out.

Fig. 8 is a transverse sectional view of the dies for forming the body and head of a bolt after the blank has passed through the dies 25 of Fig. 7.

Fig. 9 is a side elevation of a finished bolt.

Fig. 10 is a plan view of a blank after it has been pierced and spread without removing any of the metal.

30 Fig. 11 is a similar view of a blank after it has passed through the second step of the process, and

Fig. 12 is a plan view of the bolt after 35 it has passed through the next step of the process.

The object of my invention is to provide a method of manufacturing bolts in which the work of punching or piercing dies is reduced to a minimum.

40 By the methods heretofore used, the body of the blank was pierced or punched at its greatest diameter, so that the piercing or punching dies were subjected to severe strains.

45 The precise nature of my invention will be best understood by reference to the accompanying drawings which will now be described, it being premised, however, that changes may be made in steps of the method

without departing from the spirit and scope 50 of my invention, as defined in the appended claims.

Referring to the drawings, the numeral 2 designates the blanks used for carrying out 55 my method. The width of these blanks is considerably greater than the thickness and I also provide a reduced portion such as shown at 3 in the blanks. These blanks are placed in a pair of dies 4, and a portion of the center of a blank is removed by means 60 of a punch 4^a. The punched blank is then placed between forming dies 5 to shape the body and the heads, the heads being somewhat larger in diameter than the body portion, the difference in cross-sectional area 65 being equal to the amount punched out by the punch 4^a. After the bolt has been formed, the body member may be twisted about the longitudinal axis thereof and the heads screw-threaded or shaped in any de- 70 sirable manner.

If desired, I can make the bolts from blanks such as shown in Figs. 1 to 6 by first 75 piercing the center of the blanks and separating the two central members without removing any of the material, as indicated at 6 in Fig. 10, and then closing the opening and shaping the entire bolt to a cylindrical form. After the body has been shaped, as shown in Fig. 11, the ends are upset to form 80 the heads 7. The bolt can then be finished in the usual manner or, if desired, the body can be twisted about the longitudinal axis before the heads are upset.

The advantages of my invention result 85 from the provision of a method of making bolts whereby the work of the piercing or punching dies is reduced to a minimum.

I claim:

1. The method of making bolts, consisting 90 in providing a blank having a reduced central portion, then removing a portion of the metal from the reduced central portion along the longitudinal axis, and then closing said opening and shaping the body and 95 heads of said bolt; substantially as described.

2. The method of making stay bolts hav-

ing enlarged heads from a blank whose cross sectional area is approximately equal to the cross sectional area of the enlarged heads, and which is of greater width than thickness, comprising the step of removing a portion of the metal from the thinnest dimension of the blank along the longitudinal axis thereof, to form a longitudinal opening therethrough, and then closing said opening

and shaping the body and head of the bolt; 10 substantially as described.

In testimony whereof, I have hereunto set my hand.

ETHAN I. DODDS.
